UNITED STATES PATENT OFFICE

KENNETH HERBERT SAUNDERS, OF BLACKLEY, MANCHESTER, ENGLAND, ASSIGNOR
TO IMPERIAL CHEMICAL INDUSTRIES LIMITED, OF LONDON, ENGLAND

APPARATUS FOR CARRYING OUT REACTIONS CONTINUOUSLY IN THE LIQUID PHASE UNDER INCREASED PRESSURE

Application filed October 29, 1928. Serial No. 315,906.

In the art of continuous chemical processes it is well known to bring about a reaction in a liquid solution or suspension by forcing the same through a coiled pipe heated by a suitable source. If the process is carried out above the boiling point of one or more of the constituent liquids pressure will be set up and special means must be adopted for regulating the same. This has hitherto been done in either of two ways, viz: (1) by attaching to the system an hydraulic accumulator by which device a steady working pressure is maintained, or (2) by adjusting the inlet and outlet valves so that the inflow of materials is exactly balanced against outflow. Both devices are unsatisfactory in practice, the former because an accumulator is an expensive and delicate apparatus liable to fail in chemical work by corrosion, to permit leakage of dangerous material or become blocked by crystallization. The latter device requires continuous personal attention to maintain pressure balance particularly in systems of small capacity and there always remains present the possibilities of either a complete discharge of the reaction liquids or the generation of a dangerously high pressure.

I have designed, perfected and made a new device or apparatus which is suitable for continuously effecting such chemical reactions in the liquid phase at high temperatures and under substantially uniform elevated pressure. My new apparatus comprises a closed container or surrounding vessel capable of withstanding high internal pressures, this container being divided internally into two separate reaction chambers and having a substantial vapor space above said reaction chambers and in direct communication with them. This vapor space is the means by which the pressure within said closed container may be easily, effectively and advantageously maintained substantially uniform and controlled. The vapor space balances ordinary fluctuations incidental to the normal process. To assist in controlling the pressure, both in starting the process and in providing against extraordinary fluctuations in pressure, I provide means for with-

drawing vapors from said vapor space to control the pressure at such times. The separate internal reaction chambers are so arranged that they are in free unrestricted communication with each other. By this arrangement the liquid reaction mixture may freely overflow from one chamber into the other. My new apparatus is provided with suitable means for introducing and withdrawing the liquid reaction mixtures into and out of the closed container; these means being suitably arranged so that the main reaction may be effected in either the outer or inner reaction chamber as may be desired. In my new apparatus it is advantageous to have the closed container cylindrical in form and to form the two internal reaction chambers by means of a cylindrical wall centrally disposed in said container and attached to the bottom thereof. By this arrangement the tops of both the reaction chambers are completely open giving a direct communication with the vapor space and also providing a free and unrestricted communication between the reaction chambers permitting overflow of the liquid reaction mixture.

In the accompanying illustration I have shown, more or less diagrammatically, an embodiment of my invention useful in the performance of the described process. In this showing the figure is a view in vertical section with certain parts in elevation.

Referring to the structure shown in Figure 1, element 1 is a reaction vessel suitable for retaining high pressures. It is closed at both ends by lens ring joints 2. A vertically disposed central tube, open at the top, is shown at 3 leaving an annular space 4 between the walls of the reaction vessel. The lower section of the annular space 4 may be filled with Raschig rings 12 surmounted by a distributor plate 13, into which may dip a tube 8. The elements 5 and 10 are tubes leading to the lens ring joints, while elements 6, 7, 9 and 11 are valves in the respective inlet and outlet pipes.

In use, the reaction vessel may be heated or cooled by suitable means.

The liquid, in which reaction is to be carried out, can be forced in through the pipe

5, at the bottom of the annular space and will rise up therein until eventually it overflows into the vessel 3 from the bottom of which it is drawn off by the outlet valve 6. The length of the pressure vessel and the speed of flow are adjusted so that the reaction is complete when the liquid overflows. It will be seen that this simple apparatus overcomes the difficulties mentioned above, for the tube 3 and vapour space above it 10 fulfill the duties of an hydraulic accumulator by allowing the pressure to remain constant while the liquid volume varies. A device adapted to give a warning when the central tube has become full is advantageously employed.

A second liquid may be injected by way of the valve 7 and pipe 8 leading into the annular space 4. If this liquid and its reaction products are heavier than the first liquid and immiscible therein, a counter-current action results and the new product can be drawn off by the valve 9, while the spent liquor flows away by the outlet 6. Alternatively, if it is desired to protect the pressure-containing walls against an exothermic reaction, the central tube 3 may be made larger than shown, the reacting materials may be injected in it by way of the valve 6 and the product may be allowed to overflow into the annular space 4 to be drawn off therefrom by the valve 9. A pipe 10 leads to a pressure gauge; another pipe 11 may be used as outlet for gaseous reaction products. The actual arrangement and relative dimensions of the apparatus may be varied within wide limits and the above description is to be considered illustrative and not limitative.

Example:—The annular space is filled 40 two-thirds of the way up with Raschig rings surmounted by a distributor plate consisting of an annular perforated ring, into which the inlet tube 8 dips. Aqueous ammonia, preferably having a specific gravity of 0.880, 45 is forced in continuously through the pipe 5 and heated until the pressure reaches 80 to 100 atmospheres. Molten p-chloro-nitrobenzene is forced into the ammonia stream by means of the pipe 8 at such a rate that none 50 reaches the bottom of the annular space, but all is converted into p-nitroaniline which overflows into the central tube with the ammonia and is drawn off at 6 in solution in the ammonia stream, and isolated in any convenient manner.

What I claim and desire to secure by Letters Patent is:—

1. An apparatus for carrying out reactions continuously in the liquid phase under increased pressure, comprising two concentric chambers, the inner one being without a top, so that there is a space at the top common to both chambers, inlet and outlet pipes for the admission of the reagents and the exit of the reaction products, means for heat-

ing or cooling the outer chamber, an inlet pipe and an outlet pipe opening at the bottom of the outer chamber, a pipe opening at the bottom of the inner chamber, a pipe passing through the cover and descending into the outer chamber, below the open top of the inner chamber, and an additional outlet pipe opening at the common space at the top of the two chambers, the annular space being partly filled with Raschig rings 75 mounted by a distributor plate into which dips the pipe passing through the cover and descending into the outer chamber, said distributor plate consisting of an annular perforated ring.

2. An apparatus for continuously effecting reactions in the liquid phase under increased pressure, said apparatus comprising two reaction chambers, one of said chambers enclosing the other, the inner chamber being 80 in open unrestricted communication with the outer chamber, a substantial vapor space common to both chambers, thus permitting liquid reaction mixtures to freely flow from one chamber to the other without sealing 85 said vapor space from said chambers, means for introducing and withdrawing liquid reaction mixtures into and out of said chambers, and means for controlling the pressure in said vapor space.

3. An apparatus for continuously effecting reactions in the liquid phase under increased pressure, the said apparatus comprising two separate reaction chambers, one disposed within the other, the outer chamber having 90 walls capable of withstanding relatively high pressures, said inner chamber being so disposed in the outer chamber as to leave a relatively large vapor space common to both chambers and permit free flow of a liquid 95 reaction mixture from one chamber to the other without sealing said vapor space, means for introducing and withdrawing reaction mixtures into and out of said chambers, means for controlling the pressure in 100 said vapor space, and means for regulating the temperatures within said chambers.

4. An apparatus for continuously effecting reactions in the liquid phase under increased pressure, said apparatus comprising a closed 105 pressure resisting container divided into two reaction chambers, said reaction chambers being in open unrestricted communication with each other and having a relatively 110 large vapor space common to both, means for introducing a liquid reaction mixture 115 into one of the said reaction chambers, said means being such that the liquid reaction mixture is forced through the first reaction chamber and overflows into the second reaction chamber, means for removing said liquid reaction mixture from the said second reaction chamber, means for controlling 120 the temperature in said reaction chambers and means for removing vapors from the 125

said vapor space to control the temperature within the said closed container, the various means being so arranged that the liquid reaction mixture may be introduced and withdrawn from the said closed container while maintaining the pressure therein substantially constant.

5. An apparatus for continuously effecting reactions in the liquid phase at high temperature and under substantially uniform elevated pressures, said apparatus comprising a closed pressure resisting cylindrical container, said container being divided by an internal cylindrical wall into two concentric reaction chambers, said reaction chamber being closed at the bottom and open at the top, the said opening at the top being so arranged to provide a substantial vapor space common to both reaction chambers and permit free overflow of a liquid reaction mixture from one reaction chamber to the other, means for introducing a liquid reactant under pressure into the outer reaction chamber, means for introducing a second reactant against pressure into said outer chamber, means for withdrawing the liquid reaction product from the inner reaction chamber, means for withdrawing vapors from said vapor space to control the pressure in said closed container, and means for controlling the temperature within said closed container.

6. An apparatus for continuously effecting chemical reactions in the liquid phase at high temperatures and substantially uniform elevated pressures, said apparatus comprising a closed cylindrical container capable of withstanding relatively high internal pressures, a cylindrical wall centrally disposed in said container thereby forming an outer and an inner reaction chamber, a vapor space above said reaction chambers, said vapor space being common to both reaction chambers and in direct communication with each of said reaction chambers, means for introducing a liquid reaction mixture in the bottom of said inner reaction chamber, said means being such that the said liquid reaction mixture is forced upward in the chamber causing the reaction mixture to freely overflow into said outer chamber, means for withdrawing said liquid reaction mixture from the bottom of said outer chamber, and means for withdrawing vapors from said vapor space to control the pressure within said closed container.

7. An apparatus for continuously effecting chemical reactions in the liquid phase under substantially uniform increased pressure, said apparatus comprising a vertical tubular member, with closing members positioned at each end of said tubular member and securely but detachably secured thereto, sealing members positioned between said closing members and said vertical tubular mem-

ber for sealing the joints between such members, said assembled members forming a closed pressure resisting container, a second vertically disposed tubular member mounted and secured to the lower closing member, the second tubular member being closed at the bottom by the lower closing member and open at the top, the second tubular member being shorter than the first tubular member, thus dividing the said closed container into two reaction chambers one surrounding the other and providing a vapor space above and common to the said reaction chambers, an aperture in said lower closing member and means attached thereto for introducing and withdrawing a liquid reaction mixture into and out of the internal reaction chambers, an aperture in the upper closing member and means attached thereto for introducing a reactant into the outer reaction chamber below the top of the second vertical tubular member, apertures in the lower sealing member and means attached thereto for introducing and withdrawing a liquid reaction mixture and reactants into and out of the outer reaction chamber, apertures in the upper sealing means and means attached thereto for withdrawing vapors from said vapor space and for indicating the pressure in said vapor space, the said apparatus being readily disassembled and assembled for inspection and cleaning.

8. The process of continuously effecting reactions in liquid phase in which the liquid products formed are soluble in the reaction mixture, which comprises forming a relatively narrow vertical column of a liquid reaction mixture, maintaining said column at reaction temperature, thereby effecting the reaction within said liquid reaction mixture, continuously introducing liquid reactants in the lower part of said vertical column and causing the liquid reaction products to continuously overflow from the top of said column into an outlet zone laterally of the vertical column while maintaining a liquid seal above the overflow and maintaining super-atmospheric vapor pressure above and common to both the vertical column and the outlet zone, and continuously withdrawing liquid reaction products.

In testimony whereof I affix my signature.
KENNETH HERBERT SAUNDERS.
